BUCKLES

Hans Erdmann, Maplewood, N.J., assignor to Waldes Kohinoor, Inc., Long Island City, N.Y., a corporation of New York

Application October 8, 1953, Serial No. 384,946

3 Claims. (Cl. 24—73)

This invention relates to improvements in buckles, and more particularly to an improved adjustable buckle of the type which may be adjusted by being bodily moved along the length of its strap or the like which it secures, so that the strap may be made longer or shorter according to individual requirements.

Broadly stated, an object of the invention is the provision of an adjustable buckle which may be shifted along the length of its strap to a desired position of adjustment both easily and unobtrusively.

Another object of the invention is the provision of an adjustable buckle characterized as in the foregoing, which may be released from its strap to effect change of buckle position either by changing the angular relation of strap to buckle, or by relieving the pull on the strap occurring during normal use thereof.

A further object of the invention is the provision of an adjustable buckle characterized as in the foregoing, which is so constructed and arranged that the strap with which it is associated may be threaded through the buckle generally in the plane thereof; that is to say, without folding of the strap under the buckle.

Yet another object of the invention is the provision of an improved adjustable buckle of the type in which the strap with which it is associated may be threaded more or less freely through the buckle to assume a position generally parallel thereto, in conjunction with a clamping member carried by the buckle and which operates in response to normal pull exerted on the strap to clamp the buckle thereto and thereby arrest movement of the buckle.

A more particular object of the invention is the provision of an adjustable buckle of the type which may be slid along the length of the strap with which it is associated to effect tightening and loosening of said strap, and which is provided with a simple yet highly effective pivoted clamping member for securing the buckle to strap in any desired position of adjustment along the length thereof.

Yet another object of the invention is the provision of an adjustable buckle as last above specified, wherein the clamping member is of the pivoted lever type and is so associated with the buckle that it exercises its clamping function in response to pull on the strap occurring during normal use thereof, while at the same time is operative to release itself from the strap when pull or tension on the strap is relieved or by changing the normal angular relationship of strap to buckle.

The above and other objects and features of advantage of an adjustable buckle according to the invention will appear from the following detailed description, reference being had to the accompanying drawings illustrating preferred physical embodiments thereof, wherein:

Fig. 1 is a top plan view of the improved buckle according to the invention;

Fig. 2 is an end view of the buckle viewed from the right side, Fig. 1;

2

Fig. 3 is a bottom plan view of the buckle illustrated in Fig. 1;

Fig. 4 is a section taken along line 4—4 of Fig. 3, illustrating the clamping action exercised by the pivoted clamping member forming a part of the buckle illustrated in the preceding views;

Fig. 5 is a section similar to Fig. 4 but illustrating the strap-releasing action of the pivoted clamping member; and

Fig. 6 is a perspective view on a somewhat reduced scale of the novel buckle in use for securing, for example, the ends of a strap together.

Referring to the drawings, reference numeral 10 (Fig. 6) designates one end of a strap, belt or the like (hereinafter for convenience termed a strap) which is shown to be secured to the other end 11 thereof by an adjustable buckle B according to the present invention. Illustratively, the buckle fastens to said other end 11 of the strap by buttoning to a button 13 sewed or otherwise secured thereto, as shown.

As seen in Figs. 1 and 3, the buckle B is made in two parts, the one part designated 30 comprising a rectangular buckle frame provided with longitudinally spaced transverse forward and rearward belt slots 31, 32 respectively, and the other part designated 33 comprising a roughly J-shaped plate member which is pivoted to the buckle part 30 adjacent a front corner thereof and at a point which is disposed to one side of the forward slot 32 of said buckle part by means of a rivet 34 so as to swing in a plane parallel thereto. As will be explained, the buckle part 33 serves both as a belt clamping means and as a means for securing the buckle as a whole to the strap end 11. To provide the latter function, the buckle part 33 is formed with a forwardly projecting portion which has a key-hole slot 35 adapted to receive the button 13 on the end 11 of the strap, whereby the buckle may be detachably affixed thereto.

As also seen in Figs. 1 and 3, the forward slot 32 provided in the main buckle part or frame is widened as at 36 for approximately half its length. The short leg of the J-shaped buckle part 33 which is spaced a substantial distance from the pivot point 34 functions as a clamping arm 37 adapted to extend generally transversely to the frame and to underlie said widened slot portion 36. As illustrated, the inner edge of said clamping arm 37, which is preferably formed with teeth 38, normally aligns with the rearward edge of the forward buckle slot 32. Thus, in the inactive (non-clamping) position of the buckle part 33, the clamping arm 37 imposes no interference to the strap end 10 being threaded through the buckle to assume a position as illustrated in Fig. 6, or to the buckle as a whole being slid along the strap.

In use of the aforesaid buckle, it is buttoned to the strap end 11, and the free strap end 10 is cooperated with, i.e. threaded upwardly through rearward slot 31 and downwardly through forward slot 32 of the buckle part 30 in the manner illustrated in Fig. 6, it being here noted that the belt end 10 extends more or less straightway through the buckle; that is to say, it is not folded under or back on itself. During the threading-through operation, the clamping arm 37 either maintains itself in its inactive position, or it is so held by finger pressure applied to the hook or detent 40 which extends sidewardly beyond the edge of the buckle frame and hence is readily accessible. By reference to Fig. 4, it will also be seen that the leaving or forward-end portion of the strap overlies the forwardly disposed arm 37 of said clamping member and then passes downwardly intermediate the forward edge of said arm and the forward edge of the forward slot 32.

Assuming that the buckle has been shifted along the free end of the strap 10 to a position giving the proper length of strap, and that the latter has been applied to the

waist of the wearer, for example, normal strain applied to the strap in use thereof tends to cause the ends of the strap to separate (see arrows Fig. 4), whereby the buckle part 33 tends to swing away from its companion buckle part 30 (clockwise, Fig. 1, and downwardly, Fig. 5). Such results in the inner edge of the clamping arm 37, having the teeth 38 thereon, moving towards the front edge of the said forward strap slot 32, thereby to clamp or bind the belt portion passing through said slot against said front edge, as indicated in Fig. 4.

To release the buckle from the strap end 10, it is only necessary either to relieve the pull thereon, whereupon the buckle part 33 is free to return to its inactive position, or to change the angularity of strap ends to buckle, as by inserting the fingers beneath the forward and rearward edges of the buckle and pressing the adjacent underneath strap portions towards one another so that they extend generally perpendicular rather than parallel to said buckle, such also freeing the buckle part 33 so that it may return to its inactive position.

Preferably, the novel buckle B is also provided with means for limiting the swinging movement of the buckle part 33 with respect to the frame part 30. Illustratively, such means comprises a bent-over hook or detent 40 extending from a side edge of the buckle part 33 and engaging in a recess 41 provided in the corresponding edge of the buckle frame 30, and whose end edges provide stop shoulders 41a, 42a. Accordingly, the clamping member may swing only throughout the limited arc as defined by said stop shoulders. It will be understood that other means for limiting the swinging movement of the clamping member with respect to the buckle frame may be substituted for that illustrated.

Without further analysis, it will be seen that the above described and illustrated form of an adjustable buckle achieves the objectives therefor outlined in the above. That is to say, the buckle may be readily slid along a strap end 10 to a desired position of adjustment therealong, whereupon it clamps to the strap in more or less automatic fashion in response to normal pull applied to the strap ends when the buckle is used in the conventional manner. The buckle may be released from the strap end 10 in exceedingly simple manner as well as by unobtrusive manipulation, which latter is very desirable when applied to ladies' belts or wearing apparel. In addition to the foregoing advantages, adjustable buckles according to the invention may be inexpensively manufactured and possess a neat appearance.

Although an effective form of an adjustable buckle according to the invention has been described and illustrated in its application to straps and the like whose ends are to be fastened one to the other, it will be understood that such is illustrative only of various other applications to which the improved buckle of the invention is adapted or can be adapted.

As many changes could be made in carrying out the above constructions without departing from the scope of the invention, it is intended that all matter contained in the above description or shown in the accompanying drawing shall be interpreted as illustrative and not in a limiting sense.

I claim:

1. A two-part buckle for cooperation with a belt strap, one part comprising a substantially rectangular frame 10 having a pair of longitudinally spaced transverse slots enabling one end portion of the strap disposed in longitudinal direction with respect to the buckle to be threaded upwardly through the rearward slot and downwardly through the forward slot of said buckle, the other buckle 15 part comprising a combined buckle-to-strap fastener and strap clamping member pivotally connected to the frame at a point thereof disposed generally to one side of the forward slot thereof for swinging movement in a plane closely parallel to and underlying the plane of the frame, 20 said member having a forwardly extending portion provided with means for fastening the buckle as a whole to the other end of the strap and including a clamping arm which is spaced a substantial distance from the pivot point and extends generally transversely of the frame and is 25 normally disposed just rearwardly of said forward slot thereof, said clamping arm having a forward clamping edge which tends to move toward the forward edge of said forward slot thereby to clamp the belt portion extending through said slot against said forward edge responsive to pull exerted on the strap causing said buckle parts to swing away from one another.

2. A two-part buckle substantially as set forth in claim 1, wherein said member is roughly J-shaped and its clamping arm comprises the short leg thereof.

3. A two-part buckle substantially as set forth in claim 1, wherein the portion of the forward frame slot remote from said pivot point is widened rearwardly, and wherein said member is roughly J-shaped and its clamping arm comprises the short leg thereof and extends across said 40 widened portion in position such that its forward clamping edge normally extends in continuation of the rearward edge proper of said forward frame slot.
